UNITED STATES PATENT OFFICE.

WILLIAM E. DE CAMP, OF MACOMB, ILLINOIS.

GUIDE FOR SASH WEIGHTS.

Application filed January 13, 1925. Serial No. 2,218.

This invention relates to an improvement in guides for sash weights, and has for its object to provide a device of this character which is of extremely simple and durable 5 construction and adapted for embodiment in the weight boxes ordinarily employed in sash or window frame constructions and which is operable to guide and constrain the sash weights to partake of their proper 10 movements in a smooth and easy manner and to prevent jamming or binding of the sash weights.

Other objects and advantages reside in certain novel features of the construction, 15 arrangement and combination of parts which will be hereinafter more fully described and particularly pointed out in the appended claims, reference being had to the accompanying drawings, in which:

20 Figure 1 is a view in horizontal section showing a double window construction having a sash weight guide embodying the present invention incorporated therein,

Figure 2 is a view similar to Figure 1 but 25 showing an embodiment of the present invention adapted for use with single windows,

Figure 3 is a detail perspective view 30 showing the parts constituting the sash weight guides of Figure 1 prior to assembly in the weight box of Fig. 1, and

Figure 4 is a detail perspective view of the part constituting the sash weight guide 35 of Figure 2 prior to its assembly with the weight box of Figure 2.

Referring to the drawings, and more particularly to Figures 1 and 3, the numeral 1 designates a weight box of a double window construction, in which weight box sash 40 weights 2 operate. The guide constituting the present invention consists of two flat metal plates, designated at 3 and 4, the plate 3 having a central longitudinal slot 5 at one end and the plate 4 having a central longitudinal slot 6 at its opposite end so that the plates may be interfitted to provide four guide wings 7 which guide wings co-act with the walls of the weight box for the purpose of providing individual sash 45 weight compartments 8. The plates 3 and 4 are held in position at right angles to each other by means of end pieces 9 of re-

silient metal, the end pieces 9 being designed to be folded about the wings 7 provided by one of the plates and the said 55 end pieces having slots 10 accommodating the other plate. After being folded about one plate and having the walls of its slots 10 engaged with the other plate the end piece 9 may be riveted to the plate about 60 which it is folded, as indicated at 11, in Fig. 1. As indicated in the drawings the plates 3 and 4 extend longitudinally of the weight box and edges of the plates engage 65 the walls of the weight box.

In the embodiment of the invention shown in Figs. 2 and 4, the guide consists of a single plate 12 of sheet metal having an integral attaching flange 13 bent at right angles to the body of the plate and provided with openings 14 whereby it may 70 co-act with fastening means 15 for the purpose of securing the plate 12 in the window box, as shown in Fig. 2.

The plates 12 in Fig. 2 provide individual 75 compartments 16 for the sash weight 17.

I claim:

1. A sash weight guide comprising a pair of plates having interfitting slots, the plates being arranged at right angles to each other 80 to provide a plurality of guide wings defining in assembly completely enclosed individual compartments for the sash weights, and means for holding the plates in operative position.

2. A sash weight guide comprising a pair of plates having interfitting slots, the plates being arranged at right angles to each other to provide a plurality of guide wings, and end pieces foldable over the ends of one 90 of the plates and having slots accommodating the ends of the other plate, the walls of the said slots engaging the said other plate.

3. In combination with a weight box for sash weights, a pair of metal plates having interfitting slots and extending at right angles to each other, end pieces for holding the plates at right angles to each other and interfitting, the edges of the plates engaging 100 the walls of the weight box and the plates and the weight box providing individual compartments for the sash weights.

WILLIAM E. DE CAMP.
